JOACHIM FRIEDRICH HARTMANN, OF RICHMOND, INDIANA, ASSIGNOR TO HIMSELF, HEINRICH W. MORNINGSTAR, AND EUGENE MOVEL.

Letters Patent No. 95,224, dated September 28, 1869.

IMPROVEMENT IN HEAD-BLOCKS FOR SAW-MILLS.

The Schedule referred to in these Letters Patent and making part of the same.

To all whom it may concern:

Be it known that I, JOACHIM FRIEDRICH HARTMANN, of the city of Richmond, county of Wayne, and State of Indiana, have invented new and useful Improvements in Head and Tail-Blocks for Saw-Mills; and I do hereby declare that the following is a full, clear, and exact description of the construction and operation of the same, reference being had to the annexed drawings, making part of this specification, in which—

Figure 1 is a perspective view.

Figure 2 is a section reversed.

Figure 3 is the reversed side of the head-block.

Figure 4 is a wheel and pinion.

Figure 5 is a vibrating plate.

Figure 6 is a pinion cut in two, showing one-half of a conical-shaped hole.

The same letters, in the different figures, refer to corresponding parts.

A is the head-block, shown at fig. 1.

B is the tail-block.

C C are dovetail-slides, with scale of inches on top, one of which is also seen at fig. 3.

D D are knees, for pushing the log. Said knees slide on the pieces C C.

E E are pieces of timber, to which the head-block is secured, and on which the tail-block slides and rests. A part of one of said pieces E is shown at fig. 2.

F is a bevelled cog-wheel, also seen at figs. 2 and 4.

G is a pinion, (spur-gear,) a part of which is only seen at fig. 1, but fully shown at G in fig. 4.

H is a bevel-pinion, two of which are more plainly shown at H H in fig. 2, and half of one at H in fig. 6.

I is a vibrating piece, fully shown at fig. 5.

K is a support, attached to one of the pieces E, also partly shown at fig. 2.

L L, bearings for the levers M and shifters V, more plainly shown at L L in fig. 2.

M M are levers, with shifters V V at their ends, more plainly shown at M M in fig. 2.

N N are uprights, to serve as rests and stops for the levers M M, also more clearly shown at fig. 2.

O is a crank.

P is a shaft, to which the crank O is attached, and more clearly shown at P in fig. 4.

Q, guides for the lever R.

Q' Q' Q' Q' are holes, in which a pin or pins may be placed, alternately, to stop the lever R.

R is a lever.

S is a bearing, to which lever R is attached, having its fulcrum at the lower end.

T is a toothed piece or rack, which operates the pinion G.

U U are sliding cones, with slots at their outer ends. Said cones are more plainly shown at U U in fig. 2.

V V are shifters on the ends of levers M, which are adjusted to grooves in or around the cones U U, and

for the purpose of forcing the cones U into the conical holes in the pinions H.

W is a pin in the vibrating piece I, also seen at W in fig. 5.

X is a slot in the support K.

Y, in fig. 2, is an upright piece, attached to the support K, and not seen in fig. 1.

Z is the shafting, which meets in the centre of the upright Y.

1 1 are worms, one secured permanently on the end of the shafting, at the head-block; the other is made adjustable, that it may be shifted on the shaft or rod, to accommodate it to the tail-block.

2 2 are cog-wheels, one of which is seen in fig. 1, and the other at 2 in fig. 3.

3 is a screw on the side of the tail-block. A similar screw may be seen at 3, on the side of the head-block, at fig. 3.

4 4 are bearings at the ends of the screw 3. The same may be seen at fig. 3.

1 4 is a female screw, with which each of the knees D D is provided.

5 is a hole near the bottom of the vibrating piece I, seen in fig. 5. This hole 5 is intended to receive the screw 9, seen near the bottom of the support K, and on which the piece I vibrates.

6 6 are grooves around the cones U, more plainly seen at 6 6 in fig. 2.

7 shows half of a conical hole in the hubs of the pinions H.

8 is a hole in the vibrating piece I, through which the shaft P passes, and in which it rotates.

9, screw on which the piece I vibrates.

Construction.

I make my head and tail-blocks of any suitable hard timber, and of suitable size, and secure the head-block to the pieces E E. I make the tail-block movable or adjustable on the pieces E E, so as to suit different lengths of logs.

I make my screws 3 3 of one-inch or one-and-a-quarter-inch iron, with bearings at each end, and a cog-wheel at one end of each. Said cog-wheels should be of the proper size for a suitable number of cogs to work in the worms or screws 1 1.

The worms or screws 1 1 should be made of cast-iron, and have a hole bored through the centre, to fit the shafting Z, with a set-screw to hold them to their places on the shaft.

The bearings 4 4 may be made of cast-iron or brass, and are secured to the sides of the blocks by means of screws or bolts.

The female screws 1 4 are made of iron or brass, and are secured to the upright knees by means of screws or bolts.

The wheels may all be made of cast-iron, and of

suitable size to give the proper motion to the screws 3 3.

The supports K and L L are of cast-iron, and firmly secured to the piece E.

The pinions H should be cast with hubs on them, to admit of the boring a conical hole, to fit the cone U.

The cones U are cast of iron, with a groove around them, and should have a hole bored through them, so that they will slip easily on the shafting Z.

The levers M are best made of wrought-iron.

The rack T is of cast-iron.

The guide-piece Q may be cast, or may be made of wrought-iron, of the proper size and thickness to steady the lever R, and hold it to its place.

The lever R is made of cast-iron.

The cones, or their flanges or chambers, may have slots in, to slip over a pin in the shaft, to prevent their turning on the shaft; or a feather may be let into the shafting Z, and the cones U may have grooves cut, to slide over the feather, and thereby prevent them from turning on the shaft.

Operation.

It will be seen, that by drawing the top of the lever R toward the head-block, the rack T will turn the pinion G and wheel F, operating the pinions H H, causing the shafting Z to revolve, also the worms 1 1, which, working in the cogs of the wheels 2 2, operate on the screws 3 3. The knees D D are forced back, forcing the log before them. By placing a pin or pins in two of the holes Q, the lever R is checked. When the knees

D D have moved a proper distance for the required thickness of the lumber, by moving the top of the lever R toward the tail-block, the wheel F engaging the other pinion H, the same effect will be produced on the knees D D.

After the knees D D have gone the full distance on the scales C, they may be run back, by removing the rack T, and turning the crank O.

If it is desired that one of the knees D should remain stationary while the other is moved, one of the cones U may be drawn from the pinion H, by means of the lever M and shifter V. By this means, may be sawed tapering lumber, as one end of the shafting Z will stand still while the other is operated.

I do not claim the head or tail-block. Neither do I claim operating them, or, either of them, by means of screws. Neither do I claim a coupling; but

What do I claim as my invention, and desire to secure by Letters Patent of the United States, is—

1. The conical couplings, formed of the pinions H and cones U, in combination with the wheel F, pinion G, rack T, and lever R, with its support S.

2. The cones U U, when arranged to slide on the shaft Z, in combination with the screws I I and wheels 2 2.

3. The arrangement of the wheel F, vibrating piece I, pinion G, shaft P, pinions H H, and rack T.

J. F. HARTMANN.
